HENRY G. THAKE, OF GREAT BEND TOWNSHIP, COTTONWOOD COUNTY, MINNESOTA

REMOVABLE SIGN SUPPORTING DEVICE

Application filed July 8, 1929. Serial No. 376,622.

My invention relates to removable supports for signs, display billboards, mail boxes, etc.

On the public highways signs are placed at frequent intervals, close to the roadway, for guidance of the public. Rural delivery mail boxes are also placed near the roadway. When winter storms with snow obstruct the highway it is necessary to use snow plows for clearing the right of way. Signs and mail boxes along the way are partially or wholly buried in the snow and the snow plow frequently bends or destroys these supports. During the summer season it is necessary to mow grass and weeds along the margins of the highway and the presence of these standards is found to be a serious obstacle. Display signs for advertising purposes require to be changed.

The principal objects of my invention are to provide means for quickly and easily installing signs along the highway or in other location, for an easy and rapid removal of the signs, in order to facilitate any of the above mentioned operations and means whereby they may be easily replaced. Other objects are to provide a support which will permit of varying the height of the sign without changing or adjusting the supporting means and means whereby the sign may be rotated on a vertical axis and left in any one predetermined fixed position.

I have embodied my invention in the mechanism illustrated in the accompanying drawings in which Fig. 1 is a front elevation of a sign and support as it appears when erected. Fig. 2 is a side elevation, partly in section of a sign and its support. Fig. 3 is an elevation showing means for supporting a mail box. Fig. 4 shows the plug used for driving the lower section or supporting standard of the sign into the ground. Fig. 5 is a plug for closing the upper end of the same when the sign standard is removed and Fig. 6 shows a modified form for supporting the standard against rotation.

The numeral 1 indicates the sign supporting standard preferably consisting of a cylindrical pipe. 2 is a pipe designed to telescope over the pipe 1 and to be driven into the ground or soil 5 until the upper end is flush

therewith. Within the pipe 2 at a suitable distance from the upper end is positioned a plug 3 which may have its upper end fitted with a tenon 4 to mate with one or more corresponding grooves 4' in the lower end of the pipe 1 for the purpose of fixing the standard 1 in the desired angular position in relation to its vertical axis. Additional slots 4' in the standard 1 permits the sign to be placed at right angles or oppositely if desired or at other desired angles. If preferred a rod or rivet 4", Fig. 6, may be passed through the pipe centrally and anchored in its walls in lieu of the tenon 4.

The upper end of the standard 1 is provided with a longitudinal slot 6 in which screws 7 are adapted to slide. The sign 8 is supported in proper position by the screws 7 which are fitted with nuts 9 placed within the pipe standard 1. Adjustment is secured by loosening the screws 7, sliding the sign up or down and tightening the screws. The grooves 4' seating over the tenon 4 insure the sign being fixed in some one of several possible positions, preventing accidental rotation by the wind or other causes. It will readily be seen that under ordinary conditions the standard 1 may be lifted out of the pipe 2 and the sign thus removed, but in freezing weather water may collect between the surfaces of the standard 1 and supporting pipe 2 and freeze, thus preventing the removal of the standard 1. To obviate this difficulty a non-setting, water repelling substance or lubricant, such as heavy grease or waste oil or grease from machinery is inserted in the upper end of the pipe 2 sufficient to fill all the space when the standard 2 is inserted and thus exclude the water.

The pipe 2 is driven into the ground without deformation by inserting into its upper end a plug or cap 10 which is struck by the sledge. A plug 10' is also inserted in the upper end of the pipe 2 when the sign standard is removed to prevent entrance of foreign matter therein.

It is not my purpose to limit my invention to use for supporting signs only. In addition to this use the standards may be used for the installation of mail boxes as shown in

Fig. 3 where a bracket 11 is secured by screws 12 to the standard 1 in a position adjustable for height. The mail box 12' is secured to the top of the bracket by any suitable means. 5 The standards may also be used for supporting a temporary railing or chain to be installed at certain times or occasions on a pavement or passageway to control a crowd or close a road or street or for other purposes. 10 In supporting large display or advertising signs two or more standards 1 may be used and an obsolete sign may be removed and a new one substituted by loosening the screws 7 and sliding the sign upward until it is free 15 from the slot 6.

Standards of other shapes or forms may be used, such as square tubes, in connection with the lubricant inserted in the upper end of the pipe 2 without departing from the 20 spirit of my invention.

When the highway is obstructed with snow and it is desirable to use snow plows to clear the same, an operator precedes the plow and removes the signs and mail boxes, placing 25 them in any safe position and dropping into each socket in the upper end of pipe 2 one of the plugs 13, thus filling the hole and preventing the entrance of water which might otherwise fill the hole and freeze and prevent later replacement of the signs. Even 30 if some water should for any reason enter the space between the standard 1 and pipe 2 when in position, the presence of the lubricant which would still adhere to the surfaces 35 would prevent the ice from adhering and still permit easy removal. The lubricant also prevents oxidation of the contacting surfaces, which if otherwise present, might prevent removal of the standard.

40 What I claim is:

1. In a supporting standard, a supporting tube adapted for being embedded in the soil, a plug rigidly positioned within the tube, a rigid transverse element above the upper surface of the plug, a removable standard, and 45 grooves in the lower end of the standard adapted to cooperate with the transverse element.

2. In a supporting standard, a supporting tube adapted for being driven into the soil, a chamber in the upper end of the tube, a standard tube fitted within the supporting tube and maintained in an upright position thereby, a longitudinal slot formed in the 55 wall of the standard and extending downward from its upper end, and a sign board adjustably supported from the slot.

3. In a supporting standard, a supporting tube, a plug adapted for driving the tube into 60 the soil, a chamber in the upper end of the supporting tube, a transverse member extending across the tube, an upright standard telescoping in the upper end of the supporting tube, slots in the lower end of the standard 65 co-operating with the transverse member.

a longitudinal slot in the wall of the standard extending downward from the top, a sign board, screws secured to the signboard and passing through the slot, and nuts on the screws adapted to slide vertically and support the sign board on the standard in an 70 adjusted position.

HENRY G. THAKE.
